(57) **CLAIM**

The ornamental design for a combined plush bunny and child's blanket, as shown and described.

DESCRIPTION

FIG. 1 is a perspective view of a combined plush bunny and child's blanket showing my new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof.

FIG. 7 is a bottom plan view thereof; and,

FIG. 8 is perspective view thereof showing a flap on the child's blanket in an open position.

The broken lines shown in FIGS. 1-8 are for purposes of illustrating environment only and form no part of the claimed design.

1 Claim, 6 Drawing Sheets
